E. DIETZE.

SEAL PRESS.

APPLICATION FILED MAY 28, 1920.

1,413,106.

Patented Apr. 18, 1922.

Emil Dietze Inventor
By his Attorney
Fred W. Parker

UNITED STATES PATENT OFFICE.

EMIL DIETZE, OF BROOKLYN, NEW YORK, ASSIGNOR TO AMERICAN CASTING AND MANUFACTURING CORPORATION, OF BROOKLYN, NEW YORK, A CORPORATION OF NEW YORK.

SEAL PRESS.

1,413,106.

Specification of Letters Patent. Patented Apr. 18, 1922.

Application filed May 28, 1920. Serial No. 385,054.

To all whom it may concern:

Be it known that I, EMIL DIETZE, a citizen of the United States, and resident of borough of Brooklyn, city of New York, in the 5 county of Kings and State of New York, have invented certain new and useful Improvement in Seal Presses, of which the following is a specification, reference being had therein to the accompanying drawing.

10 This invention refers to a press for seals for many purposes, such seals as those made of lead, tin, wire, steel, etc., and more particularly it is useful with steel seals, and in that class with keylock seals so-called which 15 are used with efficiency and security on all kinds of boxes or packages bound with a metal strap, an example of such seals being found in my co-pending application for Letters-Patent on key lock box strap fastener, 20 filed August 7, 1918, Serial Number 248,796. The object of the present invention is to provide a press whose leverage will have a maximum compressing power capable of inter-clamping the metal seal and the overlapping 25 members of a strap with great force and effectiveness so that it will be virtually impossible to pull them apart or dislodge the seal without breaking or cutting. The invention therefore consists essentially in the construction, 30 arrangement and combination of the various parts, substantially as will be herein-after more fully described and then claimed.

In the accompanying drawings illustrating my invention:

35 Figure 1 is an interior elevation of my improved press, with one side of the frame removed, certain parts being in section, and indicates the movable jaws in the position they occupy when they are open and before the 40 beginning of the compressing operation.

Figure 2 is a similar view of the same parts shown in their active clamping or pressing position when closed and applying the seal to the strap.

45 Figure 3 is a vertical sectional elevation on the line 3, 3, of Figure 1.

Figure 4 is a perspective view of the overlapping ends of a box strap and one form of metal seal in readiness to be locked thereon.

50 Figure 5 is a perspective view of another example of keylock seal or fastener.

Figure 6 is a cross-section of the strap and seal on the line 6, 6, of Figure 2.

55 Similar characters of reference designate corresponding parts in the different views.

A suitable frame is provided to support the essential members of the press and allow a free operation of the movable parts, and such frame may be made in many ways, but I preferably construct this main frame of 60 the press to consist of two parallel plates 1, 1, that are secured to each other so as to leave an intervening space, open at the sides, which space is occupied in part by the movable jaws and their operating levers and in part 65 by a stationary jaw or anvil, as 2, which is held rigidly between the plates 1, by means of rivets or other fastening means, 3, 3, that pass through the plates 1 and jaw 2, the said jaw 2 being located near the edge of the 70 frame so that it may be in such a position as to be properly related to the seal when the latter is being compressed by the movable jaws in performing their functions in proximity to the jaw 2. The latter jaw has preferably a recessed outer face 2^a, formed between parallel flanges 12, 12, at the edges of said jaw, which flanges may be more or less sharp if preferred, and said recessed face controls the general shape taken by the seal 75 in bending, as shown in Figure 2; the seal before it is bent being shown in relation to face 2^a in Figure 1.

There are two movable jaws 4 pivotally supported in the frame by means of pivots 85 or pins 5, these jaws being on opposite sides of the fixed jaw 2, and operative in relation thereto. They are actuated by angular or bell-crank levers 8 pivoted to the ends of jaws 4 by means of pivots 10 that pass 90 through the jaws 4 and the right-angled bends in bell-crank levers 8, which are situated in slots in jaws 4, as shown clearly in Figure 3. The shorter arms of these bell-crank levers 8 are pivoted together by means 95 of a pivot 9, whose ends enter and are arranged to travel freely in the straight grooves 11 formed on the inner opposing faces of the sides 1 of the main frame; while the longer arms of bell-crank levers 8 are extended outwardly to serve as operating handles for these movable compressing jaws.

The faces of jaws 4 that are opposite to each other and are adjacent to the fixed jaw or anvil 2 are recessed at 6 with recesses sufficiently large to accommodate loosely the edges of the seal; and contiguous to these recesses 6 the jaws 4 are fashioned with projecting members or lips 7 that work opposite to, under and against the recessed face 2^a of 110

the jaw 2 and have the function of compressing the seal and the overlapping parts of the band or strap together to form the keylock fastener, as I shall presently more fully 5 specify.

In my co-pending application hereinabove referred to, Serial Number 248,796, I have described and claimed one form of keylock steel seal with which this press is 10 particularly useful. This is illustrated in my present drawing, with particular fullness in Figures 4 and 6, where it is shown outside the press, and in Figures 1, 2 and 3, where it is shown in the press, and in its 15 relation to the strap sections A and B with which the press operates to unite it. This form of seal consists of a plate C of steel or other metal or material, near one edge of which a pair of prongs or lips F, F, are cut 20 out to leave openings b, while near the opposite edge another pair of similar lips F, F, are similarly cut out to leave openings b, there being therefore an unobstructed space between the opposite pairs of lips sufficient 25 to allow the strap or its sections A and B to be inserted between them; or, when these lips F, F are bent outwardly to a right angle or thereabouts, the seal can be easily slipped over the overlapping sections A and 30 B after and while the latter are on the bale or package, as will be clearly seen by reference to Figure 4, which indicates the overlapping sections A and B and the seal with its struck-out prongs in readiness to be 35 slipped down over the said sections, so as to take the position shown in Figure 1 where the press is about to operate, and in Figure 2 where the press is being applied.

Suppose now that the press has its parts 40 in the position shown in Figure 1, with the handles wide apart and the movable jaws 4, 4, also open and wide apart that is to say in the position where the clamping lips 7, 7, are farthest from the face of jaw 2. After 45 the seal is placed on the strap the press can readily be placed in position to embrace the seal and strap, for the recesses 6, 6, in the movable jaws allow the plate C of the seal plenty of room after jaw 2 rests on plate 50 C as in Figure 1. If now we bring the handles together as in Figure 2, the jaws 4 will be moved more or less on their pivots 5, while the pivot pin 9 travels in the grooves 11 to the ends thereof and is stopped when 55 it reaches that point, for the compression of the seal will then be complete, for the action of pin 9 in grooves 11 will push the pivots 10 in a direction away from grooves 11 and so rotate the jaws 2 on pivots 5 as 60 to bring lips 7 against the seal. In this operation when the jaws 4 bring their lips 7 underneath and against the prongs or ears F and compress them below the strap sections A and B, it will be evident that 65 these prongs will catch the edges of the

strap pieces and press said edges closely together; and as the clamping of the press continues, the edges of the sections A and B will embed themselves in the openings b and be forced substantially through said 70 openings, it being noted as seen in the sectional view of Figure 6 that directly at the edges of sections A and B where the strain on the parts is the greatest there will be for a very short distance transversely inward from said edges a slight breaking or fracture of the sections A and B, but this fracturing will not be sufficient to weaken or injure the strap, but simply makes a tighter union of the parts, which are thus 75 by the action of the press bound very closely and intimately together, so that the fastener cannot be dislodged from the strap except by cutting or breaking it off. The face 2^a of jaw 2, with its parallel flanges 12, 12 forming a dished or curved recess, acts to curve the seal plate C as shown in Figure 2 in such a manner as to hold it more tightly on the strap and also to obviate projecting edges which might entangle other objects if 80 the plate C were allowed to remain straight, but as to this there may be a wide latitude in the shaping and I do not wish to be restricted in making same.

The press may obviously be used with 95 many different kinds of seals besides the particular keylock fastener just described.

Another similar form of keylock fastener is shown in perspective view in Figure 5. Here there is a plate D similar to plate C, 100 and pairs of prongs or lips E similar to prongs or lips F; but the difference in the seals lies in the provision of larger auxiliary or extension openings d in plate D contiguous to and communicating with the openings e out of which the lips E are struck. These additional communicating openings d from which the material has been entirely removed afford room for the spreading of some portion of the tightly compressed 105 points of straps A and B when the action of the press is severest thereon, and does not confine such expansion to the comparatively small area of the openings e.

These are two examples of keylock seals 115 or fasteners with which my improved press may be used; but it will be clear that the press is adapted for a very great variety of seals and other articles requiring an unusually severe compression to make a durable 120 and lasting union of parts. I therefore wish it understood that the press may be used with any suitable kind of seal or other article with which it may be found to serve a beneficial purpose. Further in the press 125 itself many changes are obviously possible in the shape, relation, proportions and arrangement of the mechanical elements, and I reserve the liberty and privilege of making such variations and changes as the circum-

stances of individual cases may require within the meaning of the following claims.

Having thus described my invention what I claim as new and desire to secure by Letters Patent is:

1. In a press, the combination with a frame having a guide therein, of a fixed jaw in said frame having an outer clamping face, movable jaws mounted in the frame and having recessed projecting clamping members adapted to clamp over the fixed jaw and engage articles between them and the outer face of the fixed jaw, bell crank levers pivoted to the movable jaws, and pivotal means for interpivotating said bell crank levers, said pivotal means sliding loosely in such guide in the frame.
2. In a press, the combination of a frame, a stationary jaw in said frame having an outer clamping face, movable jaws mounted in the frame and having recessed clamping members which operate opposite to the outer face of the fixed jaw on opposite sides thereof, so as to engage said outer face and engage articles between them and the outer face of the fixed jaw, operating levers for the movable jaws, means for pivoting said latter levers to each other, and a guide in the frame in which said pivotal means slides.
3. In a press, the combination with a frame, of a fixed jaw having an outer clamping face, movable jaws mounted in the frame and having projecting members which engage the outer face of the fixed jaw and clamp articles between them and said outer face, bell crank operating levers pivoted to

the movable jaws, means for pivoting said operating levers to each other consisting of a sliding member, and a guide in the frame opposite to the fixed jaw, in which guide the 40 sliding member reciprocates.

4. In a press, the combination of a frame having parallel sides, a rigid jaw securely fastened between said sides and having a recessed outer clamping face, a pair of movable jaws pivoted between the sides and recessed to provide a lip that will overhang and clamp opposite to the outer face of the fixed jaw so as to engage articles between the same and the fixed jaw, bell crank levers 50 pivoted to the movable jaws, and pivoted to each other, and guiding means within the frame opposite to the fixed jaw for controlling the sliding movement of the common pivot of said bell crank levers. 55

5. In a press, the combination of a frame consisting of parallel plates having oppositely-located guide grooves, a jaw fixed between said plates, a pair of movable jaws pivoted between said plates with their clamp- 60 ing members contiguous to the face of the fixed jaw, bell-crank levers pivoted to the movable jaws, and having their longer arms serving as handles and their shorter arms pivoted together, and means for pivoting the 65 latter consisting of a pin whose ends slide in the guide grooves of the frame and have a definite range of movement.

In testimony whereof I hereunto affix my signature.

EMIL DIETZE.
